UNITED STATES PATENT OFFICE.

MAX BRESLAUER, OF CHARLOTTENBURG, GERMANY, ASSIGNOR TO THE FIRM OF W. GRAAFF & COMPAGNIE GES. MIT BESCHR. HAFTUNG, OF BERLIN, GERMANY.

ANTIFREEZING FIRE-EXTINGUISHING COMPOUND.

No. 894,585.

Specification of Letters Patent.

Patented July 28, 1908.

Application filed November 9, 1906. Serial No. 342,664.

To all whom it may concern:

Be it known that I, MAX BRESLAUER, a chemist and a doctor of philosophy, a subject of the German Emperor, and a resident of 29 Kleiststrasse, in the city of Charlottenburg, near Berlin, Kingdom of Prussia, and German Empire, have invented a certain new and useful Antifreezing Fire-Extinguishing Compound, of which the following is a specification.

This invention has reference to a frost proof fire extinguishing agent, which is composed as essential constituent of sulfo-cyanic compounds. Solutions of certain sulfo-cyanic compounds possess to a very high degree of fire extinguishing properties and they will not freeze at a temperature as low as 45 degrees to about 50 degrees C. below zero. Of the sulfo-cyanic compounds, the salts 20 composed of the alkalies and of the alkaline earths and the sulfo-cyanic acid are chiefly to be considered in this connection. As examples reference may be made to sulfo-cyanid of potash and sulfo cyanid of lime. 25 The sulfo-cyanid compounds are dissolved in water, the solution obtained may be used alone as fire extinguishing liquid or other chemicals may be added to this extinguishing liquid for special purposes. Thus, for 30 the purpose of extinguishing in particular fire in smoke chimneys, an addition of acetate of alkali, of acetate of ammonia for instance, may be made to a solution of sulfo-cyanid of potash or sulfo-cyanid of lime. When a 35 solution of these substances is projected upon the fire, sulfureted hydro-carbon compounds are formed as a result of the decomposition of the salts and of their reaction upon each other, these compounds constituting the only 40 reliable extinguishing agent in the case of fires in smoke chimneys. Moreover, the sulfo-cyanid compounds, and among these particularly the sulfo-cyanid compounds of the alkalies and of the alkaline earths, possess the property of adapting themselves to 45 the conditions prevailing in the case of chemical fire extinguishers.

Chemical fire extinguishers present the inconvenience of freezing at low temperatures, 50 so as to become unfit for use in case of need. Other substances which would normally prevent the freezing of liquids cannot be used with success in this connection, as they either form precipitates, which would make the apparatus inoperative by clogging the open-

ings, or they are inflammable themselves and produce undesirable results, when thrown against a burning building.

The chemical fire extinguishers are filled with a solution of soda, as a rule, to which acid, and in most cases muriatic acid, is added when the apparatus is operated, for the purpose of generating carbonic acid, to produce pressure in this kind of apparatus for ejecting the liquid. Now calcium chlorid 60 would for instance present an agent for preparing a frost proof solution. However this agent is entirely useless for apparatus of the kind described, in view of the fact that carbonate of lime would be precipitated upon 65 the addition of calcium chlorid to the soda solution, the said precipitate clogging up the discharge opening of the fire extinguishing apparatus. Calcium chlorid would also be 70 unfit for use on account of its strongly hygroscopic properties, for when projected upon 75 burning timber jointly with the ordinary fire extinguishing liquid, it would be a cause of dry-rot in the buildings. The sulfo-cyanid compounds and in particular the alkali salts 80 of the sulfo-cyanic acid on the other hand can be used without difficulty in combination with the soda solution, without attacking the metal parts of the apparatus. They render 85 the soda solution absolutely proof against freezing and they do not form precipitates, which would be liable to clog the apparatus.

A decrease of temperature down to about 45 degrees or 50 degrees C. below zero is not sufficient to solidify the soda solution and 90 does not deprive it of its property of generating carbonic acid gas by the action of muriatic acid. Besides, the fire extinguishing property of the fire extinguishing liquid is 95 greatly increased by the addition of sulfo-cyanid compounds.

Both to the pure solution of sulfo-cyanid compounds as well as to their solution containing in addition other chemical substances for special purposes, an addition of glycerin 100 may be made. The latter addition may be used in those cases in particular, when the fire extinguishing liquid need not be frost proof down to 45 to 50 degrees C., and when 105 the fire extinguishing properties of the liquid should rather be largely increased by the addition of comparatively small amounts of sulfo-cyanid compounds.

In charging an ordinary fire extinguishing apparatus I use on 3 liters of water 5 kilos of 110

sulfo-cyanid of potassium and 330 grams of bicarbonate of soda.

Having thus described my invention what I claim is:

5 Anti-freezing fire extinguishing compound which consists of a watery solution of sulfo-cyanids and alkaline carbonates, substantially as described.

In witness whereof I have hereunto signed my name this 25th day of October 1906, in 16 the presence of two subscribing witnesses.

MAX BRESLAUER,

Witnesses:

HENRY HASPER,
WOLDEMAR HAUPT
